UNITED STATES PATENT OFFICE.

WILLIAM J. BOHAN, OF ST. PAUL, MINNESOTA.

EQUIPMENT FOR ROUNDHOUSES.

1,080,193.

Specification of Letters Patent.

Patented Dec. 2, 1913.

Application filed September 21, 1912. Serial No. 721,564.

To all whom it may concern:

Be it known that I, WILLIAM J. BOHAN, a resident of St. Paul, in the county of Ramsey and State of Minnesota, have invented 5 certain new and useful Improvements in Equipments for Roundhouses, of which the following is a full, clear, and exact description.

The invention relates to equipments for 10 round-houses, and more particularly to apparatus for inducing a forced draft in the fire-box of the locomotives, after they have been out of service, to expedite the generation of steam in the boiler of the locomotive; 15 to apparatus for carrying off the products of combustion escaping from the stack of the locomotive entering the round-house under steam, to the outside of the round-house, so that they will not escape into the round- 20 house; and to apparatus for ventilating the round-house.

In railroad practice, it is frequently necessary to drive a locomotive into the round house for the purpose of having its boiler 25 cleaned, washed out and refilled, or to be repaired. Except when some minor repair only is necessary, the locomotive which enters the round-house under its own steam, must have the fire in its fire-box extin- 30 guished, and after repair or being cleaned out, washed and refilled, it is necessary to rebuild the fire for the generation of steam of sufficient pressure in the boiler to restore the locomotive to service condition. An im- 35 portant desideratum in this practice, is to keep the locomotive out of service as short a time as possible, or to restore the locomotive to service condition as quickly as possible after the desired repair has been made or the 40 boiler has been refilled.

A further desideratum is to prevent the products of combustion issuing from the smoke stacks of the locomotives from escaping into the round-house and fouling the at- 45 mosphere therein. Heretofore, it has been customary to provide openings or devices termed "smoke-jacks" in the roof of the round-house for the escape of these products of combustion, but these devices permitted 50 much of the heat in the round-house to escape with the products of combustion and did not, if counter-draft was encountered, carry all of the products out of the round-house, because they were not adapted to make a tight

joint or be connected to the stacks, and de- 55 pended upon natural draft to carry off the products.

The present invention designs to provide an improved equipment for round houses whereby a forced draft may be induced in 60 the fire-boxes of the locomotives, by apparatus adapted to be connected to the stacks of the locomotives, to lessen the time usually consumed in generating steam in the boiler of sufficient pressure for service, and thus ef- 65 fect substantial economy in restoring the locomotives to service condition after they have been out of service. This equipment, in addition to effecting this important econ- 70 omy, serves to carry off all products of combustion, either when the locomotive enters the round-house or during the time when fire is used to generate steam. Further, this equipment provides means for ventilating the round-house when desired. 75

The invention provides apparatus which may be connected to the locomotives in any of the stalls of a round-house, to induce the necessary draft for proper and rapid combustion in starting the fires in the locomotives; provides means for regulating or modifying the draft, as desired; provides for conveyance of all of the products of combustion from the locomotives to the outside of the round-house, and provides for the venti- 80 85 lation of the round house.

A further important feature of the invention is that the steam-blower line usually provided in round houses for forcing the draft when getting up steam in the boiler 90 may be dispensed with.

The invention consists in the several novel features hereinafter set forth and more particularly defined by claims at the conclusion hereof. 95

In the drawings: Figure 1 is a plan illustrating a round-house equipped with the invention. Fig. 2 is a section taken on line 2-2 of Fig. 1. Fig. 3 is a section upon an enlarged scale showing the flexible pipe-connections for conducting air or the products of combustion to the exhaust main. Fig. 4 is a detail section of the flexible connection for permitting the lateral pipe to swing vertically. Fig. 5 is a detail section of the joint 100 for permitting the uptake to be swung laterally. Fig. 6 is a detail section showing a portion of the uptake which is adapted to 105

fit on the stack of the locomotive. Fig. 7 is a detail, partly in section, of the connection shown in Fig. 5.

A denotes a round-house which may be of usual construction, having tracks or stalls *b* therein for the locomotives, as usual and as well understood in the art.

An exhaust main 10, preferably overhead, extends around the round-house near the posts *c*, and this main is connected to a pair of suction-fans 11 and 12 by branch-pipes 13 and 14 which are connected to the intakes of the fans, respectively, and a vertical branch 15 of said main. The outlets of the fans are connected to a stack 16 which extends through the roof of the round-house and is open at its upper end for the escape of the products of combustion or fluids forced therethrough by the fans.

20 At each stall, a connection is provided whereby a tight-joint may be made with the stack of a locomotive, so that draft may be induced, in desired degree, in the boiler-flues and boiler-furnace of the locomotive.

25 The connection for each stall comprises an upwardly extending branch or pipe-section 20 communicating with the main, a horizontal pipe 21 or lateral leading into pipe 20, and an uptake section or pipe 22, having a flared terminal or hood 24 which is shaped to fit tightly against the upper end of the stack of the locomotive and to make substantially an air-tight joint for the effective induction of draft in the furnace of the

30 boiler and for conducting the products of combustion to the exhaust-main without permitting any of the products to escape into the round-house. Hood 24 is bolted to a ring 25 fixed on the lower end of pipe 22. A ring 26 is secured to the upper end

40 of pipe 22 and the outer end of lateral pipe or branch 21 has an elbow which extends into ring 26. The latter is loose around the terminal of pipe 21 to permit the uptake to swing laterally relatively to the lateral pipe.

45 A ring 27 or packing is secured to pipe 22, and serves as a flexible closure for the joint between the ring 26 and section 21. Pipe 22 is flexibly connected to the downturned end of pipe 21, by a pivotal connection consisting of bearings 28 on ring 26, and lugs 29 on a ring 30 secured to pipe section 21, which permit flexure of the uptake 22 inwardly or outwardly, according to the position of the stack in the round-house. Bolts 31 serve to hold the ring 26, and pipe 21 is in connected relation. This structure exemplifies a pipe which is flexible in the direction of the track.

50 60 The outer end of pipe 21 has its downturned end flexibly connected to pipe 20 to permit vertical swing of said pipe and the uptake suspended therefrom. Rings 23 and 34 are secured to pipe 20. These rings are 65 formed to provide a closure between these

70 pipes which permits flexure of one relatively to the other, ring 34 being flexible for this purpose. Ring 33 is formed with seats 35 at the sides thereof, which are adapted to receive pintles 36 on a ring 37 which is secured to pipe 21. This flexible or pivotal connection between pipe 20 and the laterally extending pipe 21 permits said pipe to be swung upwardly or downwardly according to the height of the stack on the locomotive, 75 and so that the inlet terminal or hood 24 may be brought into snug contact or close fitting relation with the upper end of the stack of the locomotive. These connections thus exemplify a flexible pipe-connection 80 for permitting the intake terminal to be connected to stacks of different heights and to be placed into close fitting or substantially air-tight relation therewith.

85 A tilting beam 40 is pivotally suspended from a hanger 41, as at 42, and a counter-weight 43 is connected to the outer end of this beam by a rod 44. The other end of the beam is connected to ring 25 on the lower end of the uptake pipe 22, by stirrups 46. 90 This counter-weight and beam serve to hold the flexible pipes and their connections elevated when they are not in use. Beam 40 extends angularly and to one side of pipe 22, so that the counter-weights 43 will be 95 disposed in convenient position around the stalls where they will be easily accessible. These weights serve to hold the flexible pipe elevated and may be removed when it may be desired that the weight of a beam should 100 be utilized in making a firm joint between the stack and the hood.

105 A butterfly valve 48 is pivoted in each of the branch-pipes 20 and the stem 49 of each valve is extended to one side of its pipe and has an arm 50 secured thereto. These valves are adapted to cut off or close pipes 20, respectively when the connections are not in use, so that when the fans are being operated for exhausting air or products, through one or more connections for the other stalls, air will not pass into the main through the connections which are not in use. Each valve also serves to regulate or modify to a nicety, the draft, as desired, when air is being 110 drawn through the connection for the purpose of firing up or expediting combustion in the furnace of the boiler. A rod 52, which has its lower end provided with notches 53 and is adapted to be held in different positions by a bolt or pin 54 in a guide-loop 55, has its upper end connected to a bell-crank 56 which is connected, by a link 57, to the arm 50 on the valve-stem. By adjusting rod 52, which is extended into 115 convenient position between the pits for convenient manipulation, the valve controlled thereby may be closed to prevent ingress of air through the flexible connection when that might be desired, and the valve may be 120 125 130

held in different positions to regulate or modify the draft, according to the draft desired in any particular locomotive for any particular purpose.

5 It will be understood that the plant will include a branch from the main for each stall so that any desired number of locomotives may be exhausted at the same time.

When the locomotive has been out of service, and is to be placed in service, the intake terminal or hood 24 at the stall where the locomotive is, will be lowered into engagement with the stack of the locomotive. For the purpose of permitting this to be done, despite variation in the height of the stack, or in the position of the stack in the round-house, the flexible connections which permit vertical and lateral movement of the hood or mouthpiece are employed, and to avoid escape of the fluid in the pipe and prevent escape to the round-house, these joints and connections are made air-tight. When the fans 11 and 12 are operated, air and the products of combustion will be drawn through the fire-box of the locomotive, the boiler-flues and the stack of the locomotive, thence through uptake 22, lateral 21, and main 10 to the fan and then exhausted through the stack 16. A number of locomotives may be fired up at the same time in this manner, it being necessary only to open the necessary valves 48 for that purpose. Furthermore, by opening the valves more or less, the desired degree of vacuum may be produced in the pipe-connections for proper, effective and rapid combustion in locomotives of different sizes and types.

Obviously, the apparatus may be used to carry off the products of combustion from locomotives entering the round-house with fire in the fire-box, so that the round-house will not be filled with smoke therefrom. The apparatus may also be used to ventilate the round-house when desired, by the manipulation of valves 48, so that air will be drawn through one or more of the hoods which are not connected to locomotive stacks.

50 The invention is not to be understood as restricted to the details set forth, and these may be modified within the scope of the appended claims without departing from the spirit and scope of the invention.

55 Having thus described the invention, what I claim as new and desire to secure by Letters Patent, is:

1. A round house equipment comprising an exhaust main, a pipe section projecting and extending laterally from said main, means connected to the free end of said section for connecting it to the stack of a locomotive, said pipe section being pivotally connected at its other end to the exhaust main to permit it to be swung, to bodily

raise and lower said connecting means into and out of engagement with the stack of a locomotive.

2. A round house equipment comprising an exhaust main, a pipe section projecting and extending laterally from said main, an up-take pipe connected to the distal end of said laterally extending pipe having means at its lower end for connecting it to the stack of a locomotive, said pipe section having its other end pivotally connected to the exhaust main to permit it to be swung vertically to bodily raise and lower the connecting means and the up-take pipe.

3. A round house equipment comprising an exhaust main having an upwardly extending branch thereof, a pipe section projecting and extending laterally from said main having a downwardly extending end, means connected to the free end of said section for connecting it to the stack of a locomotive, and means for pivotally connecting it at its other end to the branch on the exhaust main to permit it to be swung bodily to raise and lower said connecting means into and out of engagement with the stack of a locomotive.

4. A round-house equipment comprising an exhaust main, a horizontally extending pipe having downwardly turned ends, one of said ends being pivotally connected to said main to permit the pipe to swing in a vertical plane, an up-take pipe pivotally connected to the other end of said horizontal pipe and means for connecting the up-take to the stack of a locomotive.

5. A round-house equipment comprising an exhaust pipe formed of sections, having means at one end for connecting it to the stack of a locomotive and having its other end connected to an exhauster, a pivotal connection between the sections and a flexible ring between the pipe terminals.

6. A round-house equipment comprising an exhaust pipe formed of sections, having means at one end for connecting it to the stack of a locomotive and having its other end connected to an exhauster, and a flexible connection between the sections comprising pintles and open bearings or seats on the pipe terminals respectively, and a flexible ring between the pipe terminals.

7. A round-house equipment comprising an exhaust pipe formed of sections, having means at one end for connecting it to the stack of a locomotive and having its other end connected to an exhauster, and a flexible connection between the pipe sections comprising pintles on one section and bearings on the other, one of the sections having an enlarged terminal into which the terminal of the other is extended, and a flexible ring between the terminals.

8. A round-house equipment comprising an exhaust main, a pipe-section communicat-

- ing with said main, a horizontal pipe, means for pivotally connecting one end of said horizontal pipe to said pipe-section to permit the horizontal pipe to swing, said means comprising a ring having oppositely disposed seats constituting a bearing, mounted on the upper end of said upwardly extending pipe, a flexible ring on said first named ring and engaging the lower part of the end of said pipe, pintles in said oppositely disposed seats and an up-take section or pipe flexibly connected to the other end of said horizontal pipe for swinging laterally thereof.
- 15 9. A round-house equipment comprising an exhaust-main, a pipe-section communicating with said main, a horizontal pipe, means for flexibly and pivotally connecting one end of said horizontal pipe to said pipe-section, for swinging the horizontal pipe in a vertical plane, said means comprising a ring having oppositely disposed seats constituting a bearing, mounted on the upper end of said upwardly extending pipe, a flexible ring mounted on said first named ring and engaging the lower part of said dependent end, a ring on said dependent end having dependent projections, adapted to work in said oppositely disposed seats,
- 20 30 and an up-take section or pipe flexibly and pivotally connected to the other dependent end of said horizontal pipe for swinging laterally thereof.
10. A round-house equipment comprising an exhaust main, an upwardly extending pipe-section communicating with said main, a horizontal pipe having dependent ends, means for flexibly and pivotally connecting one end of said dependent end to said pipe-section, an up-take section or pipe and means for flexibly and pivotally connecting said up-take section to the other dependent end of said horizontal pipe comprising a ring secured to said up-take section pro-
- 25 40 45 vided with oppositely disposed bearings, a flexible ring mounted on said first named

ring and engaging the lower part of the other dependent end, a ring on said dependent end having projections adapted to work in said bearings, and means to hold the ring on the up-take section and the ring on the dependent end in connected relation.

11. A round-house equipment comprising an exhaust main, an upwardly extending pipe-section communicating with said main, a horizontal pipe having dependent ends, means for flexibly and pivotally connecting one end of said dependent end to said pipe section, an up-take section or pipe, and means for flexibly and pivotally connecting said up-take section to the other dependent end of said horizontal pipe comprising a ring secured to said up-take section provided with oppositely disposed bearings, a flexible ring mounted on said first named ring and engaging the lower part of the other dependent end, a ring on said dependent end having projections adapted to work in said bearings and bolts extending through the ring on the up-take section and the ring on the dependent end to hold them in connected relation.

12. A round-house equipment comprising an exhaust main, an upwardly extending pipe-section communicating with said main, a horizontal pipe having dependent ends, one of said ends being flexibly connected to said pipe-section for swinging the horizontal pipe in a vertical plane and an up-take section or pipe flexibly connected to the other end of the said horizontal pipe for swinging laterally thereof, a ring fixed on the lower end of said up-take section, a hood bolted to said ring on one side, and upstanding stirrups secured on the other side, a bracket member pivotally secured to said stirrups, and counterbalancing-means secured to said bracket-member.
